LIQUID DISPENSING CAP FOR A BOTTLE
OR THE LIKE

Norman A. Greene, New Rochelle, N.Y.

Application June 23, 1958, Serial No. 51,467

Term of patent 14 years

(Cl. D2—3)

Fig. 1 is a side elevational view of a liquid dispensing cap for a bottle or the like showing my new design;

Fig. 2 is a side elevational view thereof in depressed position and with a portion of the spout broken away and a portion of the upright pipe omitted for convenience of illustration;

Fig. 3 is a top plan view of the liquid dispensing cap for a bottle or the like;

Fig. 4 is a side elevational view taken from the right of Fig. 1 and with the spout element omitted for illustrative purposes only; and

Fig. 5 is a bottom plan view thereof.

The dominant features of the design reside in the portions shown in full lines.

I claim:

The ornamental design for a liquid dispenser cap for a bottle or the like, substantially as shown and described.
